UNITED STATES PATENT OFFICE.

CHARLES W. THOMPSON, OF BARRE, VERMONT, ASSIGNOR OF ONE-HALF TO FRED A. GREARSON, OF BARRE, VERMONT.

SURFACING-TOOL.

944,523.

Specification of Letters Patent. Patented Dec. 28, 1909.

Application filed March 18, 1909. Serial No. 484,136.

To all whom it may concern:

Be it known that I, CHARLES W. THOMPSON, a citizen of the United States, residing at Barre, in the county of Washington and State of Vermont, have invented certain new and useful Improvements in Surfacing-Tools; and I do declare the following to be a full, clear, and exact description of the invention, such as will enable others skilled in the art to which it appertains to make and use the same.

This invention relates especially to surfacing tools operated by pneumatic power for use in cutting granite, marble or the like but the invention is not limited to such use.

The object of the invention is to provide a simply constructed and efficient surfacing tool composed of separable members having means for rigidly connecting them together without the use of screws or bolts.

With this and other objects in view, the invention consists of certain novel features of construction, combination and arrangements of parts, as will be more fully described and particularly pointed out in the appended claims.

In the accompanying drawings, Figure 1 is a side elevation partly in section of a surfacing tool constructed in accordance with this invention; Fig. 2 is an end elevation taken from the cutting end; Fig. 3 is a vertical, transverse section taken on line 3—3 of Fig. 1; Fig. 4 is a perspective view of the head of the shank, detached; Fig. 5 is a perspective view of one of the wedge members detached and taken from the inside thereof; Fig. 6 is a similar view taken from the opposite side or outer face; and Fig. 7 is a perspective view of the clamping band or collar, detached.

In the embodiment illustrated, a handle or shank, 1, is shown preferably composed of soft steel tempered to insure strength and which is preferably made cylindrical at its outer end to fit in the socket of a pneumatic machine by which the tool is operated.

The tool holding end of the handle is provided with an integral head, 2, preferably made angular in cross section being here shown as square with shoulders as 3 formed at the corners of the base of said head for a purpose to be described. The outer free end of this head, 2, is provided with a longitudinally extending integral cut receiving member, 4, projecting from the center of the

head and having webs or jaws as 5, extending laterally therefrom and arranged at right angles to each other to provide angular seats to receive the detachable cuts or chisels as 7, which are preferably made square in cross section and are provided with the usual pointed cutting ends as 8, their other ends being flattened to fit squarely against the bottom of the seats of the head, 2, which seats form continuations of the cuts or tools, 7, and receive the thrust of said tools when the device is in operation, one corner of each tool fitting between two of the right angularly arranged webs as 5.

A plurality of cut holding and bracing members as 9, shown in detail in Figs. 5 and 6 are designed to engage the outer corners of the tools or cuts, 7, and the head, 2, spanning the joint between them and bracing them laterally at this point. These members, 9, perform the double function of braces and webs being made in the form of right angularly shaped corner clips with their inner faces adapted to fit the square corners of the head, 2, and cuts, 7, and have their inner ends closed as shown at 10, to form hooks for engaging the shoulders, 3, at the base of the head, 2, to hold said members, 9, against longitudinal outward movement. The outer faces, 11, of these members, 9, are thickened gradually toward their outer open ends to form wedge-like faces for engagement by the clamping ring or band to be described.

Fitting over and surrounding the jaws, 5, the cuts, 7, and braces, 9, is a clamping band or collar, 12, shown in detail in Fig. 7. This band is preferably made in the form of a truncated hollow pyramid with the larger end thereof arranged outwardly for coöperation with the wedge faces of the members, 9, to securely lock the cuts or tools, 7, in operative position when forced firmly over said members.

In use the tool is usually held in a vertical position pointing downward. The effect of the vibratory movement when the tool is connected with a pneumatic machine is to force the clamping band farther and farther forward over the wedge-like members, 9, and thus constantly tighten the hold of said band on the tools; yet when the tool is disconnected from the operating machine the cuts or chisels may be readily removed by simply forcing the clamping band rearward

or by holding said band and striking on the free end of the shank.

From the foregoing description, taken in connection with the accompanying drawings, the construction and operation of the invention will be readily understood without requiring a more extended explanation.

Various changes in the form, proportion and the minor details of construction may 10 be resorted to without departing from the principle or sacrificing any of the advantages of this invention.

I claim as my invention:

1. A tool holder having an angular head 15 at one end thereof, a longitudinally extending member arranged at the end of said head and having laterally extending webs or flanges arranged at right angles to each other with seats formed therebetween at the 20 inner ends thereof, wedge-like brace members having means for engagement with said head and adapted to engage the tool to be carried thereby, and a clamping band flaring outwardly toward one end and adapted 25 to encircle said wedge members to securely clamp the tool in position.

2. In a surfacing tool the combination of 30 a shank having a square head at one end thereof provided with an integral, longitudinally extending centrally disposed member having flanges extending laterally from the sides thereof with seats formed at their inner ends, cutters mounted on said seats,

wedge members provided with means for engaging said head to prevent longitudinal movement in one direction and adapted to engage said cutters, and a clamping band tapering toward one end and arranged to encircle said wedge members, and cuts, to clamp the latter in operative position.

3. In a surfacing tool the combination of 40 a shank having a square head arranged at one end thereof, said head having shoulders at its inner end, a centrally disposed, longitudinally extending member projecting 45 from the front end of said head and having laterally extending webs arranged at right angles to each other and tapering toward their forward end, with seats formed at their inner ends, a plurality of tools arranged in said seats to form a square, wedge members having right angularly shaped inner faces adapted to engage the corners of 50 said tools and provided with means at one end for engaging the shoulders of said head, and a hollow truncated pyramid shaped 55 clamping band adapted to slide over said wedge members and tools to hold the latter in operative position.

In testimony whereof I have hereunto set 60 my hand in presence of two subscribing witnesses.

CHARLES W. THOMPSON.
